United States Patent Office.

THOMAS J. BOTTOMLEY, OF BURLINGTON, WISCONSIN.

Letters Patent No. 67,489, dated August 6, 1867.

IMPROVED TUG-HOLDER.

The Schedule referred to in these Letters Patent and making part of the same

TO ALL WHOM IT MAY CONCERN:

Be it known that I, THOMAS J. BOTTOMLEY, of Burlington, Racine county, Wisconsin, have invented a new and improved Tug-Holder; and I do hereby declare that the following is a full, clear, and exact description thereof, which will enable others skilled in the art to make and use the same, reference being had to the accompanying drawings, forming part of this specification.

The present invention relates to an attachment to the harnesses of horses for holding the tugs or traces when unhitched from the whiffle-tree, and thus obviating the necessity of tying them in a knot or knots, which oftentimes causes the traces to crack, as well also as the throwing of the traces over the back of the horse, from which, by the walking or motion of the horse, they frequently fall or drop, and thereby become entangled.

In the accompanying plate of drawings my improved holder for tugs or traces is illustrated—

Figure 1 being a side view of the same, and

Figure 2 a plan or top view.

A, in the drawings, represents my improved holder for tugs or traces. This holder consists of a base or disk, B, with a slot or opening, C, through which is passed the strap called the crupper of the harness, that leads or runs from the centre of the saddle-tree along the back of the horse to the tail, by which strap the holder A is attached to the harness, and when in position is at or near the point where the hip-straps cross the said crupper-strap. C², a centre upright post on disk B, which post has two side upright curved arms D, forming one part of jaws E, the other part of which is composed of spring-levers or arms F, hung so as to swing upon the upper end of the centre post C, these levers F closing upon the upper ends of the curved arms D, and acting to hold within the openings H, embraced by such arms, the tug or trace-straps, when inserted or passed therein, by pressing them inward.

By a holder for traces or tugs of the construction above described the tying of the traces into a knot when unhitched is obviated, and a means is provided by which they can be held free of the ground, and thus out of the way of the horses' feet and legs while walking or moving.

Having thus described my invention, what I claim as new, and desire to secure by Letters Patent, is—

A holder for tugs or traces of harnesses, constructed and applied to harnesses substantially as and for the purpose described.

The above specification of my invention signed by me this 26th day of February, 1867.

THOMAS J. BOTTOMLEY.
